UNITED STATES PATENT OFFICE.

EUGENE C. STACY, OF TIFFIN, OHIO.

LOAD BINDER.

Application filed July 2, 1924. Serial No. 723,774.

To all whom it may concern:

Be it known that I, EUGENE C. STACY, a citizen of the United States, residing at Tiffin, in the county of Seneca and State of Ohio, have invented a new and useful Load Binder, of which the following is a specification.

This invention relates to load binders, and more particularly to binders of that type utilizing a lever and connections thereon whereby a chain or other flexible tie device extending around a load can be tightened.

One of the objects of the invention is to provide a load binder which can be subjected to excessive strains without danger of separating the parts.

Another object is to provide a load binder which is simple, durable and compact, is formed of but few parts and can be assembled readily.

A further object is to provide a load binder having bearing members of peculiar configuration which operate to prevent spreading of the tool while in use.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings

Figure 1 is a side elevation of the load binder.

Fig. 2 is a plan view thereof showing, by broken lines, the manner in which the same will ordinarily spread when subjected to excessive strain.

Fig. 3 is an enlarged view partly in plan and partly in section of a portion of the load binder.

Referring to the figures by characters of reference 1 designates a crooked or angle lever, one end portion of which is forked as shown at 2 while the other end portion constitutes a handle 3. A link 4 is pivotally mounted within the forked end portion of the lever, it being connected to the angle portion of said lever preferably by means of a rivet 5. This link 4 has an eye 6 in its outer end which can be swiveled therein

and to the eye is connected a link 7 which engages a hook 8. The free end of the forked portion of the lever is provided with laterally extending studs 9. As shown 60 particularly in Fig. 3 these studs are tapered inwardly toward their bases. The said studs project through openings 10 formed in the sides of a yoke or clevis 11. This yoke is so proportioned as to straddle the forked 65 portion of lever 1 when said lever is in load binding position. An eye 12 can be swiveled or otherwise connected to the yoke and may be connected by a link 13 to a hook 14. In using the device herein described 70 the handle 3 of the lever is swung approximately to the position shown by broken lines in Fig. 1 so that the link 4 and its hook 8 will thus be removed from the yoke 11 and its hook 14. The two hooks 8 and 14 can 75 then be placed in engagement with links of a chain or other flexible element that has been extended around a load to be tied or bound. After the parts have thus been placed the lever is swung in the direction 80 indicated by the arrow in Fig. 1 so that the forked end thereof will swing into the yoke 11 and bring the pivot 5 past the dead center. The pull due to the tension of the 85 tight chain or other flexible element will tend to keep the lever pressed against the crown portion of the yoke as shown in Fig. 1 and it will not be possible to loosen the load without pulling the handle 3 so as to move pivot 5 past the dead center. Ob- 90viously by providing a structure such as described, the same is rendered self-locking.

A load binder such as has been described is usually employed where it is desired to bind loads of heavy materials such as iron pipes, telegraph poles, lumber, etc., and for the purpose of lifting extremely heavy loads. It has been found in practice that should cylindrical bearing studs be provided upon the sides of the forked lever for engagement 100 by the clevis 11, the tool, when subjected to an excessive load or strain will tend to spread at the forked end of the lever as shown by broken lines in Fig. 2, this being due to the tendency of the yoke or clevis 11 105 to work outwardly along the cylindrical studs toward the ends thereof. By actual test a tool using cylindrical studs, when subjected to an excessive load, is spread both at the yoke or clevis 11 and the forked end of the lever, and the natural tendency of the parts when thus spread is to separate.

- The inwardly tapered studs 9 have been devised as a means for preventing this spreading action of the tool. By tapering these studs inwardly toward their bases, the 5 increasing strain to which the tool is subjected while a load is being lifted or bound, will tend to crowd or deflect the ends of the yoke or clevis 11 inwardly toward the forked end of the lever and not outwardly away 10 from said end. Consequently the danger of the tool spreading under the conditions mentioned is positively eliminated and a more durable and efficient device is provided than could otherwise be obtained.
- 15 What is claimed is:—
1. A load binder including a lever having a crooked or angle end portion forked, a link pivotally mounted in the angle portion of the forked end, bearing lugs extending outwardly from the sides of the forked end of the lever adjacent the free ends thereof, said lugs being tapered inwardly toward their bases, and a clevis pivotally mounted upon the studs and adapted 20 to straddle the crooked or angle portion of the lever when the connection between the link and lever is moved past a dead center.
  2. A load binder including a lever having a forked angle end portion, laterally extending studs upon the free end of said forked portion, said studs being tapered inwardly toward their bases, a link pivotally mounted within the angle portion of the forked lever, a yoke adapted to straddle 25 said angle portion and having eyes for receiving the tapered studs, said studs and yoke cooperating when the binder is subjected to strain, to draw the eyes of the yoke toward each other and toward the sides of the lever.
  3. A load binder including a lever having a forked end, said end being crooked to provide an angle portion, laterally extending studs upon the free end of the forked portion of the lever, said studs being tapered inwardly toward their bases, a link pivotally mounted within the forked portion of the lever at the angle thereof, a yoke pivotally mounted on the studs and 30 adapted to straddle the slotted portion of the lever with the point of connection between the link and lever past the dead center, and means connected to the link and yoke respectively for engaging opposed portions of a tie device, to bind a load, said yoke and the tapered studs cooperating when the load binder is subjected to strain, to prevent spreading of the yoke and lever.
  4. A load binder including a lever with 35 a forked end, said end being crooked to provide an angle portion, a yoke pivotally connected to the free end of the forked portion of the lever, a link pivotally mounted within and connected to the angle portion of the lever, means connected to the yoke and link respectively for engaging opposed portions of a load tying element, said lever being mounted to swing into the yoke about its points of connection with the yoke 40 to bring the point of connection between the lever and link past the dead center, and cooperating means upon the yoke and lever for deflecting the ends of the yoke inwardly toward the lever when the binder is subjected to excessive strain.

In testimony that I claim the foregoing as my own, I have hereto affixed my signature in the presence of witness.

EUGENE C. STACY.

Witness:

W. M. MYERS.
